UNITED STATES PATENT OFFICE.

WILLIAM BARBER, OF BRIDGEPORT, PENNSYLVANIA.

CARDING-MACHINE.

No. 923,003.

Specification of Letters Patent. Patented May 25, 1909.

Application filed February 28, 1903, Serial No. 145,542.

To all whom it may concern:

Be it known that I, WILLIAM BARBER, a citizen of the United States, residing in Bridgeport, Pennsylvania, have invented certain Improvements in Carding-Machines, of which the following is a specification.

My invention relates to that class of carding machines or carding engines in which the fibrous material is passed through the machine or engine in an unbroken sliver, sheet or web, to a pair or set of rub rolls by the action of which such sliver, sheet or web after it has been divided by suitable means, such as are usually provided, is formed into slubbing.

The slubbing may be made without any preliminary washing or scouring of the material, or any previous combing of the sliver, sheet or web.

20 The object of my invention is to straighten the fiber and thereby take advantage of the long staple of the material operated upon, producing a better slubbing than has been possible in carding machines of the general type.

My invention is fully illustrated in the accompanying drawings, in which:

Figure 1, is a view in diagram of sufficient of a carding machine to illustrate my invention; Fig. 2, is a similar view illustrating a modification of my invention; Fig. 3, is an enlarged sectional view illustrating a detail of my invention, and Figs. 4 and 5, are views illustrating further details of my invention.

35 My improved carding means may be employed with wools or other fibers in the grease, if desired, or with washed and scoured stock.

40 The object of my invention is to make a smoother, evener and stronger yarn than has heretofore been made, which is especially useful in the manufacture of carpets and other fabrics in which the yarn is cut for pile effect, but which may be used to advantage for any textile material. The fiber being straighter, the yarn is evener and stands up better.

45 In Fig. 1, 1 represents the main cylinder, covered as usual with the ordinary card clothing and rotated in the present instance in the direction of the arrow *x*. Arranged in regular order around this cylinder are the workers 2 also covered with card clothing, the teeth of which are set in the same manner as those of the main cylinder, which teeth, however, are opposed to the teeth of

the main cylinder directly opposite the former. Adjacent to each of the workers 2 are the strippers 3, shown in detail in the enlarged view Fig. 3, which strippers are covered with textile fabric, leather or other suitable material that will insure a smooth or comparatively smooth surface. By "comparatively smooth" I mean a surface that will support the sliver in a continuous unbroken web or fleece. The workers and strippers rotate in the direction indicated by the arrows. As clearly illustrated in the drawings, the sliver, sheet or web of the material under operation in passing around the main cylinder is alternately caught up from the main card by the workers and removed from said workers by the strippers and passed onto the main cylinder again. I find in practice that a smooth or comparatively smooth surfaced roller will act as a stripper to remove the fleece from the workers and pass it onto the main card.

50 The strippers being covered with leather or other smooth material can be set very close to the cylinder, say 1/64 of an inch. When the card is in operation the surface of the strippers readily covers with grease or other foreign matter contained within the material under operation, causing complete contact of the grease covered stripper with the cylinders. The friction of the wire covered cylinder against the grease covered stripper removes any excess of grease thereby keeping the contact even and uniform. The 55 fiber, by this close and even contact of the strippers and cylinder, is spread all over the cylinder in an even and uniform manner, thus allowing an equal portion of the stock or fiber to be taken by the doffing rings.

55 If so desired, the wipe roller or stripper may be fluted, as shown in Fig. 4, or have small holes bored into it, as shown in Fig. 5, thus further enhancing the stripping qualities. In both instances, the surfaces will be 60 smooth or comparatively smooth, and will have a solid body in contradistinction to the penetrable body surface formed by the card clothing.

65 The strippers 3 being coated with leather or other smooth material and presenting a substantially smooth and solid surface to the clothing of the cylinder and tension rollers, allow the fibers to pass over the surface of said strippers; not entering the same as in 70 the case where rolls covered with card clothing are employed. Furthermore, I am en-

abled to use workers much larger in diameter than usual, thereby bringing a greater surface of the card clothing into contact with the stock between the cylinder and said 5 workers, as the stock is not carried over the top of the workers in the manner common to the old process of carding.

The object of my invention is to effect a drawing and straightening of the fibers as the 10 sliver, sheet or web leaves said strippers. To do this, I arrange tension rolls 4, as shown in Fig. 1, which rolls lie over close to or in contact with the strippers 3, and being rotated in the proper direction, effect a drawing 15 action between said rolls and the strippers while the fibers are being taken up again by the main cylinder card, causing the fibers to lengthen out and straighten, thereby removing from the finished slubbing the twisted 20 and confused appearance usually present. By having smooth or comparatively smooth surfaced rollers for the strippers, the drawing and straightening action is enhanced and the fiber is not likely to be torn as with a 25 roller having toothed clothing. The web after it passes the final worker may be carried to any suitable mechanism for dividing it into strips, which strips are afterward passed to the rub rolls which form them into 30 the slubbing noted. The rolls 4 may be of plain metal, but I prefer that they shall be covered with leather or other suitable material, as shown at 5 in Fig. 3, and they are arranged to be adjusted from and toward the 35 strippers so as to regulate the amount of tension and drawing effect upon the fibers of the web.

In Fig. 2, I have shown another form of 40 apparatus for carrying this drawing operation into effect as the fleece is passed through the carding machine. This consists in providing a pair of tension rolls, which I have indicated at 4^a, which rolls are preferably covered as indicated with reference to the 45 rolls 4, and are arranged adjacent to the strippers so as to receive from the same the web or sheet under operation. In this form of my invention, the drawing will be effected between the tension rolls 4^a and not between 50 one of said rolls and one of the strippers.

The main cylinder of the carding machine is preferably speeded as under ordinary circumstances and the workers are run slower and the strippers at the same speed as the 55 workers or slightly in excess of such speed, as may be desired. The rolls 4 and 4^a, however, have a surface speed about the same as the strippers.

The improved mechanism forming the 60 subject of my invention may be used on fin- isher (condenser) card, first and second breaker, separately or in connection with all of them simultaneously. It is applicable for the preparation of the fibers of wool, cotton, 65 silk, flax and jute, for the combing process;

for the carding or combing of wool for worsted, worsted waste, ring waste, shoddy, or any other material in which straightening carding or combing is desired, or used.

Having thus described my invention, I 70 claim and desire to secure by Letters Patent:

1. The combination of a main carding cylinder, a worker roll mounted adjacent thereto and serving to catch up the stock from the cylinder, a smooth-surfaced stripping roll 75 for passing the stock back to the cylinder, and a rotatable smooth-surfaced roll of less diameter than the stripper adjacent to the latter and in nominal contact therewith for imparting tension to said stock as it passes 80 between said rolls onto the cylinder.

2. The combination of the main carding cylinder, a worker roll adjacent thereto and serving to catch up the material from the main cylinder, a smooth surfaced stripper 85 for passing the material from the worker back to the main cylinder, and means for imparting tension to the material as it passes from the stripper to the main cylinder.

3. The combination of the main carding 90 cylinder, a worker mounted adjacent thereto and serving to catch up the material under operation, a smooth surfaced stripper in proximity to and serving to receive the material from the worker, and a tension roll 95 also having a smooth surface mounted adjacent to the stripper for the purpose of engaging the web as it is fed to the main cylinder again, the contact of said roll with the stripper effecting the drawing and straightening 100 of the fiber of the material under operation as the latter is carried forward.

4. The combination of the main carding cylinder, a series of workers adjacent thereto and adapted to catch up from said main card 105 the material under operation, a series of smooth surfaced strippers adjacent to said workers to remove the material and pass it again to the main card, and tension rolls mounted in proximity to the strippers, and 110 serving to engage the fleece as it passes from said strippers to the main card.

5. The combination of the main carding cylinder, workers adjacent thereto, smooth surfaced strippers adjacent to said workers 115 and serving to remove therefrom the material under operation, and smooth surfaced tension rolls adjacent to the strippers and adapted to act with said strippers to pass the material back to the main cylinder, said tension rolls serving to draw and straighten the 120 fibers of the material.

In testimony whereof, I have signed my name to this specification, in the presence of two subscribing witnesses.

WILLIAM BARBER.
